BY Fisher & Mervit ATTYS.

UNITED STATES PATENT OFFICE.

JOHN N. HAHN, OF CLEVELAND, OHIO.

STAPLE.

951,393.

Specification of Letters Patent.

Patented Mar. 8, 1910.

Application filed April 6, 1909. Serial No. 488,300.

To all whom it may concern:

Be it known that I, JOHN N. HAHN, a citizen of the United States, residing at Cleveland, in the county of Cuyahoga and State of Ohio, have invented certain new and useful Improvements in Staples, of which the following is a specification.

My invention relates to improvements in staples, all substantially as shown and described and particularly pointed out in the claims.

In the accompanying drawings, Figure 1 is a perspective view of my new and improved staple. Fig. 2 is a plan view thereof, and Fig. 3 is an end view. Fig. 4 is a side elevation and Fig. 5 is a cross section thereof. Fig. 6 is an enlarged sectional elevation of the staple centrally lengthwise through the prongs and shown inserted in a double fold or layer of stock which the staple is adapted to lock together as hereinafter fully described.

As thus shown the staple is formed up in suitable dies from a sheet or strip of suitable sheet metal, such as a heavy grade of tin, steel or the like, and while the staple is, of course, adapted to more than a single use, as must be obvious, it was invented more especially to meet the demands for an improved fastening in a line of paste-board boxes which have a double set of flaps at their bottom foldable at right angles to each other and which have to be firmly fixed together by some means or other for handling and shipping. The said flaps being folded inward from the sides one upon the other, they are secured by two or more staples fixed in each bottom. Thus, in Fig. 6 the stock shown represents a portion of a paste-board box bottom in which the flap 2 is inside the box and flaps 3 outside thereof, and staple S is inserted from the outside across the meeting line of the outer flaps and through the corresponding inner flap. The other staple in the bottom would engage through the other inner flap not shown but like the one shown, and then by bending and clenching the ends of the prongs 4 flat against the inside of the bottom the work is done so far as the staples are concerned. However, as to this matter of securing the flaps, it should be known that heretofore the practice has been to simply paste or cement the flaps together and there was no other fastening means. But paste alone has been found insufficient because the stock

out of which these boxes are manufactured is stiff or rigid like a wooden board, and when moistened for pasting is liable to warp or curl and to thus render the paste 60 ineffective. Hence the necessity of means for locking the stock or flaps together other than the paste alone, and which according to my invention supplements the paste or cement. That is, I employ the paste as 65 formerly, which helps to make a sealed bottom for finely divided or pulverized goods and prevents creeping or leaking between folds, and apply the staples in addition after pasting and folding the flaps. This not 70 only locks the flaps firmly together but prevents their separating as they do otherwise while the paste is setting. The staples therefore serve at least a two-fold purpose and contribute to make a parcel which will sus- 75 tain the weight of the contents without any danger whatever that the bottom will give way when the parcel is handled.

Now, as to the construction of the staple itself, it will be seen that it is original in 80 several particulars. Thus, the back has a relatively deep raised rib 5 lengthwise thereof but terminating in this instance short of the base of said prongs and which are shown as having each a rib or bead 6 on the inside 85 and starting with the greatest depth in the body of the staple at the ends of bead or rib 5 and within the ends of said body. This throws a distinct depression 8 in the outside of the staple at the junction of the 90 prong and body and which runs down on the outside of the prong in a taper approximately half its length in this instance and which of course is opposite the rib 6 inside.

It is to be especially observed as an im- 95 portant feature in the construction of the springs that the rib or bead 6 runs out or ends about midway the length of the prongs and that said prongs are flat from that point to their extremity. This is the part 100 of the prongs which is bent and folded flat against the stock 2, and the length of the ribs 6 in said prongs is determined by the thickness of the stock to be secured whether it be relatively greater or less than herein 105 shown.

In view of the foregoing it will be seen that my improved staple is especially adapted to fasten paste-board, especially corrugated board, without breaking down or tearing the paper lining or body laterally thereof, because the flat ends 4 of the prongs are 110

easily bent without bowing, kinking or bending that portion of the prongs which lies within the body of the stock.

What I claim is:

- 5 1. A staple formed up from sheet metal and having a rib located centrally lengthwise outside on its back and prongs with ribs on their inside starting in the ends of the said rib on the back of the staple and 10 terminating in a taper substantially at the middle of the prongs.
2. A staple having a raised rib in its back terminating within the ends of the back and provided with prongs having tapered 15 ribs on their inside starting with their greatest depth at the base of said rib on the back and tapered thence to about the middle of

the prongs lengthwise, the portions of said prongs below said ribs being flat and adapted to be bent to clenching position.

20

3. A staple having a reinforcing rib outside on its back and prongs having ribs inside gradually reduced in cross section from end to end and extending from the ends of said rib in the back of the staple to approximately the middle of said prongs and said back having straight flat sides parallel to the rib therein.

25

In testimony whereof I affix my signature in presence of two witnesses.

JOHN N. HAHN.
